ADJUSTABLE ROCKING CHAIR

Filed Sept. 22, 1924

2 Sheets-Sheet 2

UNITED STATES PATENT OFFICE.

JACOB AARON HILL, OF WINSTON-SALEM, NORTH CAROLINA.

ADJUSTABLE ROCKING-CHAIR.

Application filed September 22, 1924. Serial No. 739,947.

To all whom it may concern:

Be it known that I, JACOB A. HILL, a citizen of the United States, residing at Winston-Salem, in the county of Forsyth and State of North Carolina, have invented certain new and useful Improvements in Adjustable Rocking-Chairs; and I do declare the following to be a full, clear, and exact description of the invention, such as will enable others skilled in the art to which it appertains to make and use the same.

This invention relates to an improved chair and one object of the invention is to provide a chair which may be used as an ordinary rocking chair, as an arm chair with a foot and leg support and back tilted rearwardly as far as desired, and also as a reclining chair.

Another object of the invention is to provide a chair having a foot and leg support of an improved construction, with the foot-supporting portion slidably connected with the leg-supporting portion, and to provide means for controlling sliding of the foot-supporting portion so that when the leg-supporting portion is swung forwardly and upwardly by link members connecting the leg-supporting portion with the tilting back the foot-supporting portion will be extended and retracted and thus at all times kept in the proper position with respect to the leg-supporting portion.

Another object of the invention is to so construct this chair that the amount of rearward incline of the back may be controlled by the person occupying the chair and to further so construct the chair that when a person arises from the chair, a resilient spring member may pull upon the foot support and draw it toward a retracted position and at the same time serve to swing the leg-support downwardly and inwardly to its normal position, the links connecting the leg support with the back at the same time causing the back to be returned to the normal position. It will thus be seen that the chair will ordinarily have the appearance of a rocking chair but may be readily transformed at will into a lounging chair or reclining chair.

Another object of the invention is to so construct this chair that when the back has been swung rearwardly as far as desired, it may be firmly braced against additional

rearward movement and therefore retained at the desired incline.

Other objects and advantages will be brought out in the course of the following detailed description.

This invention is illustrated in the accompanying drawings, wherein:

Figure 1 is a perspective view showing the frame of the chair with the back tilted rearwardly and the foot and leg rests swung upwardly to an operative position.

Figure 2 is a perspective view showing the chair tilted to expose the bottom and one side thereof.

Figure 3 is a vertical sectional view through the chair with the back and leg and foot supports in the normal position.

Figure 4 is a view similar to Fig. 3 showing the back tilted rearwardly and the foot and leg supports swung upwardly to the operative position.

This improved chair is provided with a body portion including a seat frame 1 and seat rails 2 from which extend the front and rear seat posts 3 and 4 braced by the stretchers 5 and carrying the rockers 6. It will be understood that while this chair has been shown as a rocking chair, the body portion could also be formed after the manner of an ordinary arm chair of the non-rocker type in which case the rockers would be omitted and the forward and rear seat posts directly engaged with the floor. Arms 7 are provided at the sides of the chair body and are suitably connected with the forward and rear arm stands 8 and 9, the forward arm stand being preferably secured to the side seat rails and upper ends of the forward seat posts 3 and the rear arm stands 9 being secured upon the seat frame 1 by suitable fasteners. Bracing rods 10 may also be provided to assist in bracing and supporting the arms.

The back of this chair is relatively high and is provided with side posts 11 between which are secured the upper and lower back slats 12 and 13, a strip 14 being secured to the inner face of each of the posts 11 between the slats 12 and 13 to properly space the slats and prevent them from moving toward each other out of the proper spaced relation. Hinges 15 are carried by the lower back slats 13 and secured to the seat frame 1 so that this back will be hingedly mount-

ed and may be swung from a vertical position to a rearward incline. The lower end portions of the back post 11 extend downwardly upon opposite sides of the body portion of this chair and are adapted to engage abutment faces 16 formed by recesses in the rear portion of the seat frame 1 so that the extent to which the back may be swung rearwardly may be limited and contacts between the back post and abutment shoulders or faces 16 serve to prevent the back from being accidentally moved rearwardly beyond a desired amount and the hinges 15 broken or wrenched loose.

15 The foot and leg rest or support is positioned at the front of the chair and consists of an upper or outer board or leaf 17 and an inner board or leaf 18 slidably held in engagement with the outer leaf 17 by tracks 20 forming strips 19. These strips 19 are formed of channel iron and are secured to the side edge faces of the leaf 17 with their flanges extending toward each other over the side portions of the inner leaf as shown in Fig. 2 to slidably mount the inner leaf. The outer board or leaf 17 is hingedly connected with the seat frame 1 by hinges 20 so that it may be swung vertically and in order to impart the desired 30 swinging movement to this leg support and cause it to be adjusted according to the position of the back. There have been provided links 21 positioned upon opposite sides of the body portion of the chair and pivotally 35 connected with the bearings 22 and 22' carried by the channel irons 19 and lower end portions of the back posts 11. From an inspection of Figs. 1, 3 and 4, it will be readily seen that when the back is swung rearwardly from the normal position shown in Fig. 3 to that shown in Figs. 1 and 4, the links will be thrust forwardly and they will serve to swing the leg rests forwardly and upwardly. The weight of the leg rest, links 40 and lower end portions of the back posts is such that when not in use, the back may be readily swung upwardly to the vertical position where it will be retained by the false arms 23 which constitute latch members. 45 These false arms are pivotally connected with the back posts 11 and extend forwardly through recesses 24 formed longitudinally in the rear end portions of the arms 7. The lower edge faces of the false arms rest upon the pins 25 extending outwardly from the rear arm stands 9 and notches forming rack teeth 26 are provided to receive the pins 25. It will thus be seen that when the back is 50 to be swung rearwardly to an inclined position, the false arms must be raised so that the rack teeth must pass the pins. When the back is at the desired incline, it is simply necessary to drop the false arms and the pins will engage the proper rack teeth and 55 serve to prevent the back from moving rear-

wardly any further. The teeth may however easily ride over the side pins when the back is returned to the vertical position shown in Fig. 3 and when in this position, the rear teeth of the rack will engage with 70 the side pins and prevent rearward movement of the back until the false arms have been again lifted.

The sliding foot board 18 is to be yieldably held against outward movement and 75 further supported so that when the outer leaf 17 is swung upon its hinges 20, sliding movement will be imparted to the foot board or inner leaf. Therefore, this foot board has been provided with slots 27 adjacent its sides and with an intermediate slot 28 between the slots 27. The slot 28 is open at its rear end as shown in Fig. 2 to receive the spring 29, one end of which is secured to a hook or other suitable fastener 30 carried by the outer leaf 17 and the forward end of which is secured to a staple or other suitable fastener 31 driven into the inner leaf at the forward end of the slot 28. This spring serves to normally 80 retain the foot board in a retracted position as shown in Fig. 3, but permits it to be swung outwardly when the outer leaf is swung upwardly. Pulley housings are 85 secured to the rear or underface of the outer leaf and extend through the slots 27. These pulley housings 32 carry pulley wheels 33 which are engaged by the chains 34. Each chain 34 is engaged intermediate 90 its length with its co-operating pulley wheel and has its end portions extending rearwardly, one end being connected with a hook or other fastener 35 carried by the foot board 18 and the other end of the chain being secured to a fastener 36 carried by the 95 front seat rail of the body portion of the chair. It will be readily seen that when the leg support or outer panel 17 is swung upwardly, the chains are held stationary at 100 their connections with the fasteners 36 and therefore the chains will be drawn through the pulley housings 32 about the wheels 33 and will draw upon the foot board and cause it to be slid outwardly to the extended 105 position against the action of the spring 29. When the leg support swings downwardly 110 to the normal position, the spring will be allowed to contract and in doing so will return the foot board to the retracted position. It will thus be seen that there has been provided a chair which can be used as a rocker with the parts in the position shown in Fig. 3, or the back may be swung rearwardly a desired amount or for its entire 115 extent and the chair used either as a lounging chair or reclining chair, the leg and foot support being of course swung upwardly and the foot support extended an amount corresponding to the extent of rearward incline of the back.

While the preferred form of chair has been illustrated and described specifically, it will be understood that this is only the preferred form and that the details of construction may be modified in accordance with the scope of the appended claims.

I claim:

1. A chair comprising a body, a back pivotally connected with said body for swinging movement from an upright to a reclining position, a foot and leg support including a main member pivotally connected with the front of said body for vertical swinging movement and an auxiliary member slidably connected with the main member for extension beyond the free end of the main member, means actuated from said back for vertically swinging the main member of said support when said back is moved, means connected to said body and said auxiliary member for automatically sliding the latter outwardly when the main member swings upwardly, and means for retracting the auxiliary member when the main member swings downwardly.
2. The structure of claim 1 having the means for moving the auxiliary member outwardly consisting of flexible means having one end connected with the auxiliary member and its other end with the chair body, and guide means carried by the main member with the flexible means in sliding engagement with the guide means whereby upon upward swinging movement of the main member pull will be exerted upon the

flexible means to draw the auxiliary member forwardly and outwardly.

3. The structure of claim 1 having the means for moving the auxiliary member outwardly consisting of flexible means having one end connected with the auxiliary member and its other end with the chair body, the auxiliary member having a longitudinally extending slot, and a pulley mounting secured to the main member and projecting through the slot and carrying a pulley wheel engaged with the flexible means to draw upon the flexible means and move the auxiliary member outwardly when the main member is swung upwardly.

4. The structure of claim 1 having the auxiliary member provided with longitudinally extending slots adjacent its sides and an open ended longitudinally extending slot leading from its inner end intermediate its width, a spring disposed longitudinally in the intermediate slot and having its rear end connected with the main member and its forward end connected with the auxiliary member, guide pulleys carried by the main member and extending through the side slots of the auxiliary member, and flexible means slidably engaged with the pulleys and having their end portions extending rearwardly and connected with the chair body and inner end portion of the auxiliary member.

In testimony whereof I have hereunto affixed my signature.

JACOB AARON HILL.
